C. W. MABEY

CIGAR LIGHTER

Filed Feb. 3, 1923

UNITED STATES PATENT OFFICE.

CHARLES W. MABEY, OF INDIANAPOLIS, INDIANA, ASSIGNOR TO MABEY ELECTRIC AND MANUFACTURING COMPANY, OF INDIANAPOLIS, INDIANA, A CORPORATION OF INDIANA.

CIGAR LIGHTER.

Application filed February 3, 1923. Serial No. 616,665.

To all whom it may concern:

Be it known that I, CHARLES W. MABEY, a citizen of the United States, residing at Indianapolis, in the county of Marion and 5 State of Indiana, have invented new and useful Improvements in Cigar Lighters, of which the following is a specification.

This invention relates to improvements in electric cigar lighters which are particularly 10 designed for use in automobiles where an electric current of low voltage, primarily installed for illuminating purposes and for igniting the hydrocarbon charges in the engine, is available, and where the air resistance 15 caused by the rapid motion of the car makes the lighting of a cigar difficult with a match.

The object of this invention is to provide a device that can be conveniently attached 20 by screws to the frame or other wooden members of a car and wired to the usual ignition and lighting equipment.

Another object is to provide a hot-spot member so flexibly attached to a fixed body 25 member that the hot-spot may be moved freely and positioned with one hand to locate and light a cigar and to automatically complete the electric current when so moved.

A further object is to automatically break 30 the circuit by gravity when the hot-spot member is released by the user, and the object also is to lock said member against accidental movement when released by the user and while not in use.

35 I accomplish the above, and other objects which will hereinafter appear, by the mechanism illustrated in the accompanying drawing, in which—

Fig. 1, is a perspective view of the cigar 40 lighter with the spot-light member removed from the body member or holder and manually positioned for use. Fig. 2, is a vertical longitudinal section of the body member of the lighter with the hot-spot member in full line in its raised position completing the circuit and in dotted lines in a further raised position for use. Fig. 3, 45 is a rear elevation of the body member. Fig. 4, is a vertical longitudinal section of the body member with the hot-spot member in its closed position and the circuit broken. Fig. 5, is a longitudinal section of the hot-spot holder and connecting arm, removed

from the body member, and sectioned to show the wiring. Fig. 6, is a fragment in 55 longitudinal section at right angles to the plane on which Fig. 5 is drawn, and showing the complete assembly of the hot-spot member, and Fig. 7 is a cross section on the line 7—7 of Fig. 6.

60 Like characters of reference indicate like parts in the several views of the drawing.

The body member 8 may be cast or stamped out of metal. It has a back channel 9 extending from the lower end nearly to the upper end of the body and the extreme upper end of the body is bifurcated. In the upper end of the channel 9 a metal 65 electrical contact plate 10 is secured by a binding-post 11, and it is insulated from the body member 8 by a non-conductor 12. The post 11 is connected by a wire 13, having an insulating cover, with a binding-post 14, at the lower end of the body 8 and insulated from said body. A wire 15 connects with a source of current preferably 70 the ignition system of a motor car in which the cigar lighter is installed.

Holes 16 are formed in the body 8 for 75 the passage of screws by which the device is fastened to the wooden frame or other suitable portion of the car, in any desired location.

The major upper portion of the body 8 is formed with a pair of parallel flanges 17 80 projecting forwardly from said body. Holes 18 are formed near the upper end of the flanges 17 for the reception of a pin 6 by which an arm 20 is hinged to the body member. On the inner end of this arm a 85 binding-post 21 is seated and insulated from the arm. The outer end of the arm has a socket to receive an end of a tube 22 formed out of spirally wound spring wire, the coils of which are in contact with each other. 90 The opposite end of the tube 22 enters a socket in a handle member 23, and the tube is retained in both of its sockets by forcing the walls thereof against the tube by the aid of a vise.

100 At the outer end of the handle 23 is a head 24 having a circular recess entering from one side, in which a porcelain disk 25 is fitted and removably held by a pair of diametrically opposite washers 26, that are 105 retained by screws 27, passing through the

washers into the head. The washers are clipped on one side so that, by loosening the screws, the washers may be given a half turn to a position which will allow the removal 5 of the disk past them.

Seated in the disk 25 are binding posts 28 and 29, which are connected by a resistance strip 30, wound back and forth in suitable holes formed in the disk. A narrow strip 10 of mica 31 is preferably laid between the face of the disk and said windings, at right angles with the windings on that side of the disk. A space between the disk 25 and the bottom of its recess in the head is lined with 15 an insulation 32. This insulation has a hole through it through which a leaf spring contact 33 on the inner end of a binding post 28, makes electrical contact with the metal of head 24.

20 The metal cup 34, opposite the binding-post 29, receives a leaf spring contact 35 on the inner end of said binding-post. The binding-post 29 is electrically connected by a wire 36 with a binding-post in the far end 25 of the arm 20. This post is insulated from the arm, but the head of the post is so positioned that contact with the metal plate 10 occurs when the outer end of the arm is suitably swung upwardly in using the lighter.

30 The conducting wire 36 passes through tube 22 of spirally wound spring wire, and I have found that an induced current is set up in the wire of the tube from that passing through wire 36, which objectionably heats 35 the handle and tube. This I have stopped by placing an auxiliary wire 37 beside the wire 36, one end of which auxiliary wire is seated in the arm 20 and the other end is coiled in the head 24, in the manner shown in Fig. 5.

40 Formed on the handle 23 is a lug 38 having an indent 39 in its inner end, and formed in the lower portion of body 8 is a longitudinal slot 40 just wide enough to receive the lug 38 with a loose fit. The slot is elongated and additionally widened below to make insertion of the lug easier. The distance of the bottom of the notch in the lug from the pin 6 on which the arm 20 is hinged is so regulated that the lug will be locked in 50 the notch by the tension of the spring-handle-tube 22, which is slightly flexed to insert the lug in slot 40. This adjustment is obtained in practice while assembling the arm and the tube 22 on the handle 23, by 55 first inserting the tube in the socket of the arm and crimping the walls of the socket against the tube by the aid of a vise and then pivoting the arm to the body 8 and adjusting the tube 22 in the socket of the handle 60 member so the bottom of the notch in the lug 38 will be the right distance from the pin 6, and then crimping the walls of the handle-socket against the tube as was done with the lever socket.

65 The lug 38 forms a bearing, also, for the

thumb of the operator in giving a half turn to the head so as to present its hot-spot properly to the cigar or cigarette to be lighted.

In the operation of my invention, when the handle 23 and the head 24 are released 70 by unhooking the lug 38 and raising the parts to the position shown in Fig. 1 and in dotted lines in Fig. 2, contact is made so the current passes through wires 15, 13, 75 plate 10, head 21, wire 36, cup 34, post 29, resistance 31 and post 28 to the leaf spring contact 33, and through that the head 24. From the latter it passes through 23, 22, 20 and 18 to the body 8, post 42 and out through wire 75 which is grounded on the motor car. 80

While I have here shown the best embodiment of my invention now known to me it is capable of many variations in form and arrangement of parts and I therefore do not desire to be limited unduly or any more than 85 is required by the appended claims, and what I claim is—

1. In a cigar lighter, a body member, an electric resistance, means comprising a cylinder of spirally wound wire for swingingly supporting the resistance from the body member and for manual contact in using the lighter, an electric current conductor in the body member and extending thence through said cylinder to the resistance, and a second conductor extending through the cylinder to keep the latter from heating by induction. 90

2. In a cigar lighter, a body member, an electric resistance member having a handle, means comprising a spirally wound wire cylinder and a hinge for swingingly supporting the handle from said body member, an electric conductor in the body member extending thence at certain positions of the handle to the electric resistance member, means for making the circuit by swinging the handle away from the body member and for breaking the circuit when the handle is closed against the body member, and a catch means engaged by stretching the wire cylinder for holding the handle in a closed position against the body member. 100

3. In a cigar lighter, a body member, an arm hinged to the body member, a spirally wound wire cylinder secured to the arm, a handle secured to the cylinder said handle having a recessed head, an electric heating element in the head, an electric conductor in the body terminating in a contact member at the arm hinge, a cooperating contact member carried by the arm, an electric conductor therefrom passing through the cylinder to the heating element in the head and a second conductor extending through the cylinder to keep the latter from heating by induction. 115

4. In a cigar lighter, a body member having a slot, a member swingingly connected with the body member and having a fas- 120
125
130

tening lug and also carrying an electric resistance said swinging member comprising a resilient member, said lug being adapted to enter the slot in the member and 5 removably lock the swinging member to the body, and means for electrifying the resistance to heat it.

5. In a cigar lighter, a body member, an electric heating element, an arm hinged to 10 the body member, a spirally wound wire cylinder secured to the arm, a handle secured by the cylinder, a recessed head on the handle, a disk of insulation in the recess, a pair of binding-posts carried by 15 the disk, an electric resistance connecting the posts in the disk, contact members on each post, an insulation lining in the recess between the disk and bottom of the recess having a hole through which a contact 20 member on one of the posts touches the metal of the head, a metal cup between the lining and disk in which the contact on the other post makes electrical connection, a

contact member on the arm near the hinge, an electric conductor from the resistance in 25 the head to said contact member, a contact member on the body making contact with the one on the arm in raised position of the arm, a conductor in the body connecting said contact member on the body with a 30 source of current, and means for completing the circuit between the body and source of current.

6. In a cigar lighter, a body member, a member swingingly connected therewith 35 carrying an electric resistance, and comprising in its length a cylinder formed of spirally wound wire, an electric conductor in the body and extending thence to the electric resistance, through the cylinder, 40 and a conducting wire extending through the cylinder to keep the cylinder from heating by induction.

Signed at Indianapolis, Indiana, this the 29th day of January, 1923.

CHARLES W. MABEY.
